(75) Inventor: **Fredi Bischoff**, Zurich (CH)

* cited by examiner

(73) Assignee: **IDIAG**, Volketswil (CH)

Primary Examiner—Stella Reid
(74) Attorney, Agent, or Firm—Notaro & Michalos P.C.

(**) Term: **14 Years**

(57) **CLAIM**

(21) Appl. No.: **29/137,423**

The original design for a training apparatus for breathing exercises, as shown and described.

(22) Filed: **Feb. 21, 2001**

DESCRIPTION

(30) **Foreign Application Priority Data**

Sep. 27, 2000 (XH) DM/053348

(51) **LOC (7) Cl.** **24-04**

(52) **U.S. Cl.** **D24/164**

(58) **Field of Search** D24/164; 128/205.13,
128/205.14, 205.17

(56) **References Cited**

FIG. 1 is a front, top, right perspective view of a training apparatus for breathing exercises;

FIG. 2 is a right side elevational view thereof;

FIG. 3 is a front side elevational view thereof;

FIG. 4 is a rear elevational view thereof;

FIG. 5 is a top plan view thereof; and,

FIG. 6 is a bottom plan view thereof.
